United States Patent Office.

SAMUEL CRUMP, OF NEW YORK, N. Y.

Letters Patent No. 101,830, dated April 12, 1870.

BRONZE-COLLECTING ATTACHMENT TO BRONZING-MACHINES.

The Schedule referred to in these Letters Patent and making part of the same.

To all whom it may concern:

Be it known that I, SAMUEL CRUMP, of the city, county, and State of New York, have invented a new and useful Improvement in Bronze-collecting Attachments to Bronzing-Machines, of which the following is a full, clear, and exact description, reference being had to the accompanying drawing forming part of this specification, and in which—

Figures 1 and 2 represent outside elevations at right angles to each other of my improvement as applied to a bronzing-machine; and

Figure 3, a sectional elevation of the same.

Similar letters of reference indicate corresponding parts.

In machines for bronzing labels, show-cards, and other work, the bronze being in the condition of an exceedingly fine powder, becomes scattered, and floating in the air, is not only lost to a large extent, but, being inhaled by the workmen in attendance, is very detrimental to health.

The vibration, consequent upon the rapid working of the machine, as in the case of a cylinder machine, to which the invention is here shown applied, although it is equally applicable to others, agitates and assists in scattering the bronze, so that, notwithstanding the machine is usually boxed in, to catch, in a drawer or receptacle below, the surplus bronze brushed off the printed matter in its way through the machine and otherwise settling therein, a large amount of bronze invariably escapes both through the necessary openings in the case and joints or seams therein.

To obviate this loss and injurious escape of the bronze, I attach to the bronzing-machine or case, in which the same is boxed, what I denominate a vacuum bronze-collector, and which consists of a suction-fan or device operating to draw the air from the machine or interior of its case, and, with such air, all floating or detached particles of bronze, and to expel the same along a suitable pipe or tubular passage, either to pendent canvas or other like bags, or into water in which it will be precipitated, or such loose bronze may be otherwise collected after it has been drawn off by the fan.

Referring to the accompanying drawing—

A represents an ordinary cylinder bronzing-machine, boxed in as usual by an outer case, *a*.

B is a suction-fan, operating to draw air and floating bronze from the case, and to expel the same along a tubular passage, C, which may dip at its outer end in water to collect the bronze by precipitation; but it is preferred to make this tubular passage of a crane-like form, and to attach to it, in a pendent and removable manner, at orifices *b*, made in its upper arm or portion, bags D, made of canvas, or other suitable material that will permit of the air drawn in by the fan passing out through its interstices, so as to prevent choking, but will not allow of the bronze escaping through it.

In this way, the surplus or floating bronze is deposited by its gravity, and collected in the bags as it is passed by the suction-fan along the tubular passage C.

A vacuum or suction being created within the case *a* of the bronzing-machine, and the fan B being supplied with air exclusively by the necessary openings and cracks or joints in the case, all surplus or floating bronze is passed by and through the suction-fan to the bags or receptacle arranged to receive it.

Although reference here only has been made to bronze, the invention is equally applicable and is designed to include the use of other materials for the like purpose, such as ultra-marine, Paris green, flock, and crystallized glass, any of which may be worked in the bronzing-machine.

What is here claimed, and desired to be secured be Letters Patent, is—

1. The combination of a suction-fan or device with a bronzing-machine, or the case inclosing the same, and a tubular passage connecting said case with a suitable receptacle or receptacles for collection of the floating bronze, substantially as specified.

2. The combination of the bags D with the tubular passage C, the suction-fan B, and the bronzing-machine A, or its case *a*, essentially as shown and described.
